UNITED STATES PATENT OFFICE.

MAX LOEWENTHAL, OF NEW YORK, N. Y.

DUPLEX PARALLEL SHEARS.

SPECIFICATION forming part of Letters Patent No. 596,213, dated December 28, 1897.

Application filed July 24, 1897. Serial No. 645,756. (No model.)

To all whom it may concern:

Be it known that I, MAX LOEWENTHAL, a citizen of the United States, residing in the city, county, and State of New York, have 5 invented certain new and useful Improvements in Duplex Parallel Shears, of which the following is a specification.

The object of my invention is to produce a device whereby the severance of columns of 10 printed matter from paper or "clippings" can be made with precision and expedition, which invention may also be employed in other relations.

My invention has special application to the 15 cutting of clippings from newspapers, wherein it is desirable to cut an article from the paper at any one of the columns thereof.

At the present time, so far as I am informed, it is the custom to employ shears or scissors 20 wherein but two oppositely-acting blades are employed, the blades severing but one side of the column in their progress through the paper, and with this single-shear device in order to sever a column located within the limits of 25 the outer columns or edges of the paper it has been necessary to go over each side of the column in order to sever it from the paper. With my duplex shears both of the sides of the column are severed simultaneously, re- 30 quiring the ground to be gone over but once to completely sever the column from the paper. My improvements in this regard also embody means for accommodating the sets of shears to varying widths of columns.

35 My invention therefore consists in the combination of a plurality of sets of parallel shearing or cutting blades so connected that they can be operated simultaneously by a single handle to produce a shearing or cutting ac- 40 tion at two or more points at the same time.

My invention further consists in the combination, with a plurality of sets of cutting blades, of means for adjusting the distance between the cutting-blades and setting said 45 blades in their position of adjustment.

My invention further resides in the construction and combination of parts herein-

after described, and more fully pointed out in the claims.

In the drawings forming part of this speci- 50 fication, Figure 1 is a side elevation of a device embodying my invention; Fig. 2, a plan view; Fig. 3, a side elevation of one of the sets of shears, partly in section, on the line 3 3, Fig. 2, looking in the direction of the arrow; and Fig. 4 is an enlarged sectional elevation through the blade connections on the line 4 4, Fig. 2, looking in the direction of the arrow.

Similar numerals and letters of reference 60 indicate corresponding parts throughout the several views.

The embodiment of my invention illustrated in the accompanying drawings comprises two sets of shearing or cutting blades 65 1 2 3 4, each set of blades being pivoted together by separate and unconnected pivoting and tension pins or screws 5 6 of any desired construction. The blades 1 2 are extended rearwardly, as at 7 8, to form the usual han- 70 dles 9 10, while the blades 3 4 are extended rearwardly from their fulcrum to form ex- 75 tensions 11 12.

As will be noted, the primary shears or set a, comprising the blades 1 2, is of the ordinary or usual construction, whereas the secondary or complemental shears or set b is of like construction, except that the extensions 11 12 from the pivot 6 are not formed into operating-blades, the ends of the extensions 80 11 12 being curved, as at 13, especially at their under side, to avoid presenting a sharp surface to the paper.

The duplex cutting instrumentalities comprising the sections a b are united for simultaneous operation in the following manner: To the outer blade 1, at the rear of its pivot 5, is rigidly secured an apertured bar 14, which may be hollow for its entire length or a portion thereof may be made integrally with the 90 blade 1 or separately formed and secured thereto in any desired manner, as by forming a hole in the extension 8, threading it, and forming a like thread on the end of the

bar 14 and securing the parts together. Other means of connection may be employed. The extension 7 of the blade 2 is provided with a transverse and circular slot 15 to allow the blades to be vibrated to or from each other in the operation of shearing without interference with the bar 14. The extension 7 is likewise provided with an outwardly-extending bar 16, which may be an exact counterpart of the bar 14, with the exception of the parts hereinafter described. A clamping device 17, comprising the split lips or projections 18 19, (the split *c* being continued along the side of the bar 14 for the desired distance,) is formed on the end of the bar 14 and extends outwardly at right angles therefrom, the lower lip 19 of the clamp being provided with a rounded lug 20, as shown in Fig. 4, to allow it to ride easily over the paper, both of the lips being apertured and provided with screw-threads to receive the threaded stem 21 of the set-screw 22, the end of the stem 21 being prevented from striking the paper by the lug 20. Extending outwardly from the extensions 11 12 are two bars 23 24, the bar 23 being rigidly secured to the blade 3 in line with the aperture in the bar 14 and closely adjacent the pivot 6 and the bar 24 rigidly secured to the blade 4 in line with the aperture in the bar 16 and to the rear of the bar 23, the extension 11 of the blade 3 being provided with a circular slot 25, Fig. 2, to allow the bar 24 to be vibrated without interfering with the movements of the blades 3 4. The bars 23 24 enter the apertures (which may be of any desired shape in cross-section) in the bars 14 16 and tie the respective blades, to which said bars are connected, together, so that the movement of the blades of the primary shears *a* will be communicated to that of the secondary shears *b*, causing all the blades to work in unison. The set-screw 22 fixedly secures both of the pairs of blades together.

As is apparent, the bars 23 can be moved in the direction of the length of the bars 14 16, telescoping the former into the latter to increase or diminish the distance between the blade-sections *a* *b*, the set-screw fixing them in their position of adjustment.

The points of each of the sets of blades are drawn out fine, as indicated at 26, Fig. 2, in order that the blades may be entered into the paper between its edges without tearing it.

The separation of the blades of the main or primary shears *a* in the manner indicated in Fig. 3 separates the corresponding or complementary blades of the secondary-shears section *b* by means of the connections hereinbefore described, and in like manner the corresponding blades of the shears are moved together when the blades of the main section *a* are so operated, causing the action of all of the blades to be synchronous.

I do not limit myself to the precise construction of parts hereinbefore shown and described, as it is apparent that they can be modified in many ways without departing from the spirit of my invention.

Having described my invention, I claim—

1. The combination in an article of the class described, of the primary shears comprising the blades pivoted between their ends, secondary shears comprising a set of pivoted blades disposed parallel to the primary set, an inflexible connection extending between the outer blade of the primary shears and the inner blade of the secondary shears, and a further inflexible connection extending between the inner blade of the primary shears and the outer blade of the secondary shears, substantially as described.

2. The combination in an article of the class described, of the primary shears section *a* comprising the blades 1, 2, having extensions 7, 8 and handles 9, 10, said blades being pivotally secured together intermediate their ends, a further set of blades 3, 4, disposed parallel to the blades 1, 2, and having extensions 11, 12, said blades being pivoted together intermediate of their ends, a bar extending between the blades 1, 3, and connecting them together, and a further bar extending between the blades 2, 4 and connecting them together, both bars being located at the rear of the fulcrum of each set of blades, substantially as described.

3. The combination with the two separate sets of blades, each set having a separate pivot and disposed parallel to each other, separate lateral extensions from each of the sets of blades, and means for adjustably securing said extensions together, the extensions being located at the rear of said pivots, substantially as described.

4. The combination with the blades 1, 2 pivoted together as at 5 and provided with operating-handles, the longitudinally-apertured bar 14 extending from the blade 1 at the rear of the pivot, a bar 16 extending outwardly from the blade 2 adjacent the bar 14 and to the rear of said pivot, the blades 3, 4 pivoted as at 6 and having extensions 11, 12, a bar 23 extending outwardly from the extension 11 to the rear of said pivot and movably engaging the bar 14, and another bar 24 extending outwardly from the extension 12 and movably engaging the bar 16, and means for securing either of the opposing bars together, substantially as described.

5. The combination with the blades 1, 2 pivoted together as at 5 and provided with operating-handles, the longitudinally-apertured bar 14 extending from the blade 1 at the rear of the pivot, a bar 16 extending outwardly from the blade 2 adjacent the bar 14 and to the rear of said pivot, the blades 3, 4 pivoted as at 6 and having extensions 11, 12, a

bar 23 extending outwardly from the extension 11 to the rear of said pivot and movably engaging the bar 14, and another bar 24 extending outwardly from the extension 12 and 5 movably engaging the bar 16, and a clamp comprising the split lips 18, 19, and set-screw 22, for embracing the bar 23, substantially as described.

6. The combination with the paired sets of 10 blades, and bars extending from each of the

blades of each of the sets, and a pendent lug extending from one of said bars between said sets of blades, having a rounded under surface, substantially as described.

Signed in the city, county, and State of New York this 16th day of July, 1897.

MAX LOEWENTHAL.
